CLEANER FOR PAINT ROLLERS

Anthony H. Dreyling, St. Paul, and Cecil B. Woofter,
Crystal, Minn.; said Woofter assignor to said Dreyling

Application May 21, 1956, Serial No. 41,566

Term of patent 14 years

(Cl. D9—6)

FIG. 2

FIG. 1

FIG. 3

FIG. 4

FIG. 5

FIG. 7

FIG. 6

Figure 1 is a top plan view of a cleaner for paint rollers incorporating our design.

Figure 2 is a view of the cleaner of Figure 1, from one side.

Figure 3 is a view of the cleaner of Figure 1, from its other side.

Figure 4 is a bottom plan view of the cleaner of Figure 1.

Figure 5 is a view of the cleaner of Figure 1, from one end.

Figure 6 is a view of the cleaner of Figure 1, from its other end.

Figure 7 is a cross-sectional view along line 7—7, of Figure 1.

We claim:

The ornamental design for a cleaner for paint rollers, as shown.
